(57) **CLAIM**

The ornamental design for a motor cover for vacuum cleaner, as shown and described.

DESCRIPTION

FIG. 1 is a left side perspective view taken from the front and above of a motor cover for vacuum cleaner showing my new design;

FIG. 2 is a right side perspective view taken from the rear and above thereof;

FIG. 3 is a front elevational view thereof;

FIG. 4 is a rear elevational view thereof;

FIG. 5 is a right elevational view, the left elevational view being a mirror image thereof; and,
FIG. 6 is a top plan view thereof.

The broken line showing of a tank for a vacuum cleaner is for illustrative purposes only and forms no part of the claimed design.
